UNITED STATES PATENT OFFICE

2,402,194

STAR IDENTIFIER

Lester Wolfe, United States Navy

Application December 19, 1944, Serial No. 568,916

8 Claims. (Cl. 35—43)

(Granted under the act of March 3, 1883, as
amended April 30, 1928; 370 O. G. 757)

1

This invention relates to a star identifier and has for an object to provide a star identifier in the form of a concave hemisphere with the zenith of the observer as the zenith of the star identifier.

One of the objects of this invention is to provide a star identifier in which various star groups and positions are shown exactly as they appear to the eye of the observer who views the sky facing any horizon.

Another object of the invention is to provide a star identifier in which distortions and inaccuracies, always present when showing a spherical area on a plane surface, are eliminated.

Yet another object of the invention is to provide a hemispherical star identifier in which the concave hemispherical area is manually adjustable to represent the visible sky at the desired hour of the day or night for any time of the year.

Still another object of the invention, as a manufacturing sequence, is to depict a star identifier on the outer surface of a spherical body, made of thin elastic material, collapse the same so as to form a hemisphere or bowl with a double wall in which approximately one-half of the outer surface of the spherical body forms a convex surface of the hemispherical double walled bowl and the remaining half forms the inner concave surface of the bowl which latter surface shows the star identifier to be viewed by the observer.

Another object of the invention is to provide a hemispherical star identifier, having the shape of a bowl, which is folded along a great circle line of the original hollow sphere and in which the edge or rim (great circle line) represents the horizon of the concave surface of the star identifier showing the visible sky.

A further object of this invention is to provide a pair of hemispherical members to be used in conjunction with the star identifier for making the star identifier assume a hemispherical shape with the zenith of the star identifier coinciding with the zenith of the observer and for retaining it in such hemispherical shape.

Still another object of this invention is to provide a pair of hemispherical shells, one of which is of slightly lesser diameter than the other and which lesser diameter hemisphere will be preferably of somewhat stiff transparent material having a suitable grid thereon to assist in locating the stars on the identifier.

Still another object of this invention is to provide a spherical star identifier which is held in

2

hemispherical condition by a pair of hemispherical shells of slightly different diameter, the shell of greater diameter being such that it may be located on the outside of the star identifier or inside the star identifier to act as backing member when the transparent shell of lesser diameter is operated to collapse the spherical identifier thereagainst.

Still a further object of this invention is to provide an improvement on the star map depicted in U. S. Patent No. 2,135,287 of November 1, 1938, to Houston, principally by the provision of the cooperating hemispherical shells.

Yet another object of this invention is to provide a spherical member having the entire heavens depicted thereon in such manner that when it is collapsed to form a hemisphere with the zenith on the concave portion of the hemisphere coinciding with the zenith of the observer, all, or at least the principal stars visible in the heavens will be correspondingly depicted in the concave portion of the hemisphere.

Still a further object of this invention is to provide a star identifier on a concave hemispherical surface wherein the zenith of such surface may be kept in coincidence with the zenith of the observer irrespective as the zenith of the observer may change either through passage of time or through passage of the observer over the surface of the earth.

With the foregoing and other objects in view, the invention consists in the construction, combination and arrangement of parts hereinafter set forth, claimed and illustrated in the drawings in which:

Fig. 1 is an elevational view of the spherical member forming part of this invention.

Fig. 2 is a sectional view through the spherical member of Fig. 1.

Fig. 3 is a perspective view of the inner hemispherical shell.

Fig. 4 is a bottom plan view looking into the concave side of Fig. 3.

Fig. 5 is a perspective view of the assembled star identifier in operative position.

Fig. 6 is a sectional view through the assembled star identifier.

Fig. 7 is a perspective outside view of the outer shell.

Fig. 8 is a partly sectional, partly elevational view showing the method of assembling the shells and sphere together.

Fig. 9 is a partly elevational, partly sectional view of a slightly modified form with the backing shell located within the sphere.

Fig. 10 is a sectional view of the assembled identifier of Fig. 9, and

Fig. 11 is a partly sectional, partly elevational view of an inner shell to be used with the form of Figs. 9 and 10.

There is shown at 10 a spherical member of resilient material having the principal stars 11 of the entire heavens depicted thereon in their true relationship to each other and to the equinoctial 12 as well as to 0-180° meridian line 13 together with the poles 15. However, instead of having the SHA 14 increase in a clockwise direction as it does in the normal star globe, the SHA 14 increases in a counterclockwise direction when looking down upon the celestial sphere from a point along the northerly extension of the polar axis. This arrangement is necessary because it is not the convex surface of the sphere 10 that is intended to be used in identifying the stars, but rather it is a concave surface formed by collapsing one side of the sphere into the other that is used in providing the star identifier of this invention. The sphere 10 is provided with additional intermediary meridian and declination lines 16 being printed in a tint lighter than the ones designated 12 and 13 and are for the purpose of assisting the operator in definitely marking his position on the sphere 10.

In order to collapse this sphere 10 into a hemisphere having a concave star identifier surface, the sphere 10 is provided with a plurality of vents 17 which permit easy collapse. Two shells, a backing shell 18 and an inner shell 19 of slightly lesser diameter than the backing shell 18, are provided for collapsing the sphere therebetween and holding it in the collapsed form shown in Figs. 5 and 6. The inner shell 19 is necessarily of a transparent material, being made of any suitable transparent plastic such as glass, somewhat stiff pliofilm, or any other suitable plastic, and is provided with a grid 20 together with meridian and declination lines 21 and 22, suitably marked as at 23 and 24. While these markings 23 and 24 may be on either surface of the transparent hemispherical shell 19, they are so located that they are visible from the concave surface thereof. In addition, the shell 19 may be provided with a lip or flange 25, adapted to cooperate with a corresponding lip or flange 26 on the outer shell 18.

For convenience of manufacture, the outer shell 18 may be of a similar material in which case it would be transparent, although it would likewise be serviceable if of a different material, either transparent or opaque. Suitable clips 27 may be provided for clamping the lips 25 and 26 together and holding the star identifier in assembled position.

As shown in Fig. 8 the star identifier is easily assembled by placing the zenith or pole 28 of the transparent inner shell 19 against that point on the surface of the sphere 10 corresponding to the zenith of the observer and pushing the shell 19 against the sphere into the backing shell 18, after which the clamps 27 may be put into position. The shell 19 may be of a tint corresponding to the color of meridian lines 16 on sphere 10, hence the lines 16 serve to locate the zenith when assembling, as in Fig. 8, then are invisible when viewed through the concave side of shell 19. The sphere 10 is made of a suitable material capable of receiving the data on its outer surface and of such material that it may be easily collapsed. Natural rubber is one suitable material that will

well serve this purpose, although any plastic having similar properties may likewise be used.

In the form of invention shown in Figs. 9, 10, and 11 the backing shell 29 is located permanently within the sphere 10 and the transparent inner shell 30 is pushed against the point on the sphere 10 corresponding to the zenith to collapse the sphere 10 to the star identifying form shown in Fig. 10. The shell lips are necessarily omitted on this form, although clips 31 can similarly be placed over the edges of the hemisphere thus formed to hold it in position.

In operation, after collapsing the sphere 10 so as to have the zenith of the inner shell correspond with the observer's zenith, the observer holds the identifier above his head slightly out of his line of sight to the stars that he is attempting to identify and then orients the identifier until the stars depicted thereon are in the same relationship to him as the stars visible in the heavens, thus enabling him to compare the formation in the heavens with the corresponding formation depicted in the concave surface of the identifier and locate and identify such of the principal stars visible to him as he wishes.

Other modifications and changes in the number and arrangement of the parts may be made by those skilled in the art without departing from the nature of this invention, within the scope of what is hereinafter claimed.

The invention herein described and claimed may be manufactured and used by or for the Government of the United States of America for governmental purposes without the payment of any royalties thereon or therefor.

What is claimed is:

1. As an article of manufacture, a star identifier comprising a hemispherical body composed of flexible material having the principal stars of the entire heavens depicted thereon with the SHA increasing in counterclockwise direction when observed from the northern polar direction, said spherical body being foldable at any selected circumference to the shape of a double-walled hemispherical bowl having its edge approximately a great circle to depict the heavens at any selected zenith on its concave surface, and a pair of hemispherical shells of slightly different diameter cooperating with said collapsed sphere to hold it in folded position, the shell of lesser diameter being transparent and permitting the concave surface thereof to be visible therethrough.

2. As an article of manufacture, a star identifier comprising a hemispherical body composed of flexible material having the principal stars of the entire heavens depicted thereon with the SHA increasing in counterclockwise direction when observed from the northern polar direction, said spherical body being foldable at any selected circumference to the shape of a double-walled hemispherical bowl to depict the heavens at any selected zenith on its concave surface.

3. As an article of manufacture, a star identifier comprising a hemispherical body composed of flexible material having the principal stars of the entire heavens depicted thereon with the SHA increasing in counterclockwise direction when observed from the northern polar direction, said spherical body being foldable at any selected circumference to the shape of a double-walled hemispherical bowl having its edge approximately a great circle to depict the heavens at any selected zenith on its concave surface, and a pair of hemispherical members of slightly different diameter cooperating with said collapsed sphere to hold it

in folded position, the shell of lesser diameter being transparent and having a SHA grid thereon and permitting the concave surface thereof visible through the transparent inner shell with the SHA grid superimposed on the star data.

4. For use in folding a flexible sphere having a map of the stars thereon to any selected zenith on its concave surface, a pair of hemispherical shells, one of said shells being of a diameter slightly less than the diameter of the folded sphere, the other of said shells being of a slightly larger diameter than said first shell.

5. For use in folding a flexible sphere having a map of the stars thereon to any selected zenith on its concave surface, a pair of hemispherical shells, one of said shells being of a diameter slightly less than the diameter of the folded sphere, the other of said shells being of a slightly larger diameter than said first shell, said first mentioned shell being of transparent material.

6. For use in folding a flexible sphere having a map of the stars thereon to any selected zenith on its concave surface, a pair of hemispherical shells, one of said shells being of a diameter slightly less than the diameter of the folded sphere, the other of said shells being of a slightly

10

15

20

25

larger diameter than said first shell, said first mentioned shell being of transparent material and having an SHA grid depicted thereon.

7. For use in folding a flexible sphere having a map of the stars thereon to any selected zenith on its concave surface, a pair of hemispherical shells, one of said shells being of a diameter slightly less than the diameter of the folded sphere, the other of said shells being of a slightly larger diameter than said first shell, each of such shells having outturned lips thereon and clamp means for holding said lips together to thereby hold said shells and folded sphere in star identifying assembly.

8. For use in folding a flexible sphere having a map of the stars thereon to any selected zenith on its concave surface, a pair of hemispherical shells, one of said shells being of a diameter slightly less than the diameter of the folded sphere, the other of said shells being of a slightly larger diameter than said first shell, the second mentioned of said shells being located within the sphere to serve as a backing member to said first mentioned shell.

LESTER WOLFE.
